HAIR FOUNDATION ROLL

John W. W. Holden, Providence, R. I.

Application September 1, 1937, Serial No. 161,974

6 Claims. (Cl. 132—38)

My present invention relates to the hair curling art, and has particular reference to a foundation that is left in the curl to give it shape, and to the manufacture thereof.

- 5 The principal object of the present invention is to provide a foundation for curls in the back of a wearer's head which is easily inserted and is extremely light, and which has sufficient resiliency to retain its shape.
- 10 With the above and other objects and advantageous features in view, my invention consists of a novel arrangement of parts more fully disclosed in the detailed description following, in conjunction with the accompanying drawings,
- 15 and more specifically defined in the claims appended thereto.

In the drawings illustrating my invention,

Fig. 1 is a plan view of the foundation as it leaves the braiding machine;

20 Fig. 2 is a plan view of the tool used for distending the foundation shown in Fig. 1;

Fig. 3 is a plan view of the foundation stretched upon the tool shown in Fig. 2;

25 Fig. 4 is a plan view, partially cut away, showing the distended foundation with the ends turned in;

Fig. 5 is a plan view, particularly cut away, of the completed foundation;

30 Fig. 6 is a plan view of a distended foundation of small diameter;

Fig. 7 is a plan view of the same, inserted in a tool for turning in the ends;

35 Fig. 8 is a plan view of the same, with the tool having turned in the end;

Fig. 9 is a perspective view of the foundation on the tool shown in Fig. 3, and set upon a heater; and

40 Fig. 10 is an enlarged fragmentary view of the foundation braiding.

Referring more in detail to the above drawings, the numeral 10 designates the foundation as it comes from the braiding machine. This is made with a specially coated and impregnated cotton

45 thread which gives it resiliency and which can be dyed in various hair colors to match the wearer's hair. The thread is run through a conventional braiding machine such as used for making shoe-laces, with the machine set so that a fairly wide

50 strip is braided, preferably about one-half inch; the preferred length is about one foot. The thread is preferably cotton threads, dyed and lacquer sized to produce an imitation horse hair, and is three strand, three twists to the inch; the 55 most suitable braider is a 60 braider, although a

44 braider may be used, the thread having twelve picks to the inch.

A long, slender, metal tool, tapered at one end, see Fig. 2, is then inserted into this braided strip and forced through it. This expands the braiding while contracting the strip to about one-half its original length, and gives the strip a cylindrical form, see Fig. 3. The tool 11 with the expanded strip thereon is now rolled over a heated plate 12, see Fig. 9, this plate merely comprising a steel 10 plate with electrical heating elements beneath the same; the heat and pressure set the strip in its cylindrical shape so that when it is slipped off the tool 11, it retains its new shape. The unfinished ends 13 of the wider foundations are 15 then turned in by hand, and the strip is put back onto the tool 11 and run over the plate 12 once more to press the turned-in ends tightly into the strip. The completed product 14 is a cylindrical hollow form made of braided imitation horse hair with finished ends, which is very light and resiliency, and returns to its set form when stretched or compressed.

In making foundations for small curls, it is 25 necessary to use a much narrower braided strip having a much smaller diameter. After this small strip is taken off its tool, it is difficult to turn the unfinished ends thereof in by hand, and I therefore use a special tool for this purpose. As illustrated in Figs. 6 to 8 inclusive, the small 30 braided strip 15 is squeezed together at one end and pushed partially into a cylinder 16 of slightly smaller diameter than the strip 15; a plunger 17 is then pushed through the other end of the cylinder 16 and turns the unfinished edge 18 into the strip 15, the doubled portion riding upon the outer periphery of the cylinder 16, as shown in 35 Fig. 8. The plunger 17 has a pin 19 slidable in a slot 20 in the cylinder 16 to limit its movement, and the cylinder 16 has a pair of arms 21 extending at right angles thereto for gripping the same when the plunger is forced down. After the 40 unfinished end has been turned in, the plunger and cylinder are withdrawn and the strip is finished in the same manner as the larger strip heretofore 45 described.

As is evident from the foregoing, the resultant 50 product is resilient and light, and admirably adapted to perform its intended function. The hair can be readily curled about the same, and retaining pins are easily pushed into the ends to hold it in place. It can be worn by the user without removal through the entire day and is made in any color so that it matches the color of 55 the hair and is invisible.

From the foregoing it is also obvious that by using the method described, the foundation can be economically and rapidly assembled.

Although imitation horse hair is preferred, other materials such as very fine stainless steel wire, for example, may be used if desired.

While I have described a specific form of curl foundation and a specific method of making the same, I do not wish to be limited thereto, as changes may be made to suit the requirements for different foundation designs, within the spirit and scope of the invention as defined by the appended claims.

I claim:

- 15 1. A foundation for a hair curl comprising a hollow cylinder of braided, dyed, imitation horse hair set to retain its shape and having the open ends thereof turned inwardly.
2. A method of making foundations for hair 20 curls comprising braiding a resilient material into an elongated annular strip, stretching it into the form of a hollow cylinder, and setting the cylinder by the use of heat and pressure.
3. A method of making foundations for hair

curls comprising braiding an imitation horse hair thread into an elongated annular strip, stretching it into the form of a cylinder over a tool, and setting the cylinder by the use of heat and pressure.

4. A method of making foundations for hair 5 curls comprising braiding a resilient material into an elongated annular strip, stretching it into the form of a cylinder over a tool, turning in the ends, and setting it in its final form.

5. A method of making foundations for hair 10 curls comprising braiding a resilient material into an elongated annular strip, stretching it into the form of a cylinder over a tool, turning in the ends, and setting it in its final form by the application of heat and pressure.

6. A method of making foundations for hair 15 curls comprising braiding a resilient material into an elongated annular strip, stretching it into the form of a cylinder over a tool, turning in the ends, and setting it in its final form by the application of heat and pressure by rolling it over a heated plate before removing it from the tool.

JOHN W. W. HOLDEN.
